DOOR CATCH

Filed Sept. 18, 1929

INVENTOR:
George R. Adams,
BY
Floyd M. Harris
Attorney.

UNITED STATES PATENT OFFICE

GEORGE R. ADAMS, OF LOS ANGELES, CALIFORNIA, ASSIGNOR TO L. C. SACHS, OF LOS ANGELES, CALIFORNIA

DOOR CATCH

Application filed September 18, 1929. Serial No. 393,445.

My invention relates to catches which are used to maintain doors and the like in a closed position.

Catches of this type usually have a handle which may be grasped for opening and closing the door. An operating means for releasing a catch member in the catch is usually incorporated in the handle so as to be operated by the same hand which grasps the handle, 10 the catch member being released by turning or sliding the handle relative to the body. My invention comprehends a catch of this class wherein the catch member is released by depressing a button on the catch and further 15 comprehends a catch in which the button is incorporated in the handle so that the catch may be released and the door opened with the same hand.

It is an object of my invention to provide 20 a catch of the above class which is releasable by grasping a handle of the catch between two fingers of one hand and by depressing with the thumb a push button extending through the handle.

25 Another object is to provide a novel linkage between the push button and a catch member in the catch so that the catch member is released when the push button is depressed.

The type of catch I have used in the preferred form of my invention has a catch member which is movable longitudinally of the catch body to release the catch, but catch members having other releasing means may be used, if desired.

35 A further object is to provide a novel linkage between the push button and a catch member of the above class in which a movement of the push button transversally of the catch body is translated into a movement longitudinally of the catch body for releasing 40 the catch member.

Another object is to provide a linkage of this type which has toggle links operatively connecting the body and the catch member 45 and engageable by the push button so as to release the catch member when the push button is depressed.

Another object is to provide a novel attachment between the catch member and the toggle link in which an end of the toggle link

is slidable in an enlarged opening in the catch member.

It is also an object to provide a detachable handle for a catch of the above class so as to permit the catch to be fitted with various 55 ornamental handles.

Various other objects and advantages are evidenced in the construction of the preferred form of my device.

In the drawings, Fig. 1 is a perspective view showing the utility of a device of my invention;

Fig. 2 is a sectional view taken on a plane indicated by the line 2—2 of Fig. 1 showing the parts in a normal position;

Fig. 3 is a sectional view taken the same as Fig. 2 showing the parts in a released position;

Fig. 4 is a sectional view taken as indicated by the line 4—4 of Fig. 2;

Fig. 5 is a perspective view showing the parts in the order of their assembly;

Fig. 6 is a sectional view of a part of an alternative form of my invention.

Referring to Fig. 1, I have shown a catch 75 11 of my invention which may be attached to a door 12 and which is engaged with a conventional keeper 13 attached to the door face 14 so as to hold the door 12 closed. As clearly shown in Figs. 2 to 4, the catch 11 80 has a housing or box-shaped body 16 along the sides of which are attachment flanges 17. The body 16 has an opening 18 in the side between the flanges 17 and has a frusto-conical turret 20 formed on the opposite side. 85 Adapted to surround the turret 20 is a glass handle 21 which has a frusto-conical portion 24 adapted to fit over the turret 20 and a flanged head 25 at the end of the frusto-conical portion 24, the handle 21 being thus adapted to be grasped between the first and second fingers of the hand when releasing the catch.

The handle 21 is secured to the catch 11 by a nut 28 which is threaded to the turret 20 and which has an annular flange 29 resting 90 in an annular opening 30 in the handle 21. The nut 28 is provided with a central opening 34 which connects with an opening 35 in the turret 20 and an opening 36 in the body 16. 95

Extending longitudinally of the opening 100

36 and of the body 16 is a catch member 40 having large and small rectangular portions 41 and 42 which are respectively slidable in rectangular openings 44 and 45 in the ends 5 of the body 16. The end of the large rectangular portion 41 has an angled face 46 for engaging the keeper 13 in a well-known manner, the catch member 40 being forced into engagement therewith by a compression 10 spring 50 surrounding the small portion 42 and being compressed between the body 16 and a shoulder 51 formed between the large and small portions 41 and 42.

The catch member 40 is moved from a normal position, as shown in Fig. 2, to a released position, as shown in Fig. 3, by an operating means 54 of my invention. The operating means 54 includes a primary operating member 55 having a cylindrical portion 56, the 15 end of which is rounded to form a push button 58 and which is extended through the opening 34 so that the push button 58 may be depressed by the thumb of the operator when the handle 21 is grasped by the fingers 20 in releasing the catch 11. The cylindrical portion 56 is of smaller diameter than the opening 34 so as to extend therethrough and permit the primary member 55 to move to an angled position, as shown in Fig. 3. It 25 is also tapered midway of the primary member 55 to a reduced diameter portion 60 which is slidable in a circular opening 61 in the catch member 40, the opening 61 being sufficiently enlarged to prevent binding when 30 the catch member 40 and the primary member 55 are moved to the released position, as shown in Fig. 3.

Cooperating with the primary member 55 is a secondary operating member 62 having 40 a yoke 63 formed at one end, the yoke 63 being pivoted to the primary member 55 by a pin 64 extending through openings in the yoke 63 and primary member 55. The secondary member 62 extends through an elongated opening 66 in the catch member 40 and the other end thereof is pivoted, in a manner to be subsequently explained, as at 67 relative to the body 16 so as to form a bent toggle joint between the primary and secondary 45 members 55 and 62.

The pivoting at 67 is accomplished by a retaining member 70 which closes the opening 18 in the side of the body 16 and which provides a hook 71 at one end, which hook 55 71 extends inside the body 16 and pivotally engages a slot 72 in the end of the secondary member 62. The end of the retaining member 70 is thus pivotally held between the hook 71 and the end wall of the body 16. The 60 retaining member 70 has side walls 74 which extend inside the body 16 and normally spring outward to frictionally engage the body 16 and hold the retaining member 70 in place. A portion of each of the side walls 65 74 of the retaining member 70 is cut and

turned down to form supports 76 for the catch member 40 when it is in the released position, as shown in Fig. 3.

In the operation of my invention, the handle 21 is grasped between the first and second fingers of the hand of the operator and the push button 58 is depressed by the thumb. The depressing of the push button 58 moves the primary member 55 relative to the body 16, swinging the pin 64 about the pivot 67 70 to a position A, as shown in Fig. 3, and moving the primary member 55 into engagement with the nut 28 at the point B. This forms toggle links of the primary and secondary members 55 and 62 as indicated by the line 80 C—C of Fig. 2. Further depression of the push button 58 causes the toggle links to rotate relative to each other and causes a rotation of the primary member 55 relative to the body 16. Due to the engagement of the reduced diameter portion 60 of the primary member 55 with the walls of the opening 61 in the catch member 40, the catch member 40 is caused to slide relative to the body 16 against the action of the spring 50. During 85 this movement, the reduced diameter portion 60 of the primary member 55 slides in the opening 61 and the secondary member 62 moves relative to the catch member 40 in the opening 66. When the push button 58 is 90 fully depressed the parts are moved to the fully released position, as shown in Fig. 3, and the door 12 may be opened by pulling on the handle 21. Upon releasing the push button 58 the spring 50 moves the catch member 40 to the normal position and due to the engagement of the parts the primary and secondary members 55 and 62 are also returned to the normal position, as shown in Fig. 2.

It should be noted that the size of the opening 66 is made such that when the catch 11 is in the normal position, the rear wall of the opening 66 engages the secondary member 62 and acts as a stop to prevent further forward movement of the catch member 40.

In order to disassemble my device it is only necessary to remove the retaining member 70 from frictional engagement with the body 16. This releases the end of the secondary member 62 and permits the apparatus inside the body 16 to be removed therefrom. The retaining member 70 is normally held in the body 16 by frictional engagement and it 115 is also held in the body 16 when the catch 11 is secured to a door 12 by being held between the catch 11 and the door 12. This prevents the retaining member 70 from becoming accidentally detached from the body 16 when the catch is installed for use.

In Fig. 6, I have shown an alternative form of my invention in which the glass handle 21 and nut 28 are replaced by a metal handle 86 which has a threaded flange 81 for thread-

ing on the turret 20. Other types of handles may be used to secure various ornamental effects as desired.

Various modifications may be made in my device without departing from the spirit of my invention. The catch member 40 which I have used is movable longitudinally of the body 16, but this may be replaced by catches having other movements. It should also be noted that the primary and secondary members 55 and 62 are essentially a pair of toggle links which operatively connect the body 16 to the catch member 40. It is possible to provide the attachment between the primary member 55 and the catch member 40 with a pivotal connection and to form the push button 58 separately from the primary member 55, the push button 58 engaging the toggle links so as to release the catch member 40 when the push button 58 is depressed.

I claim as my invention:

1. In a catch, the combination of: a body adapted for detachable connection to a support; a handle on said body adapted to be grasped between two fingers of a hand; and a push button extending through said handle and adapted to be moved transversely of said body when depressed by a thumb so as to release said catch.

2. In a catch, the combination of: a body adapted for detachable connection to a support; a catch member carried by said body and movable relative thereto; a handle on said body adapted to be grasped between two fingers of a hand; a push button extending through said handle and adapted to be moved transversely of said body when depressed by a thumb; and means operatively connecting said catch member and said push button for moving said catch member relative to said body when said push button is depressed.

3. In a catch, the combination of: a body adapted for detachable connection to a support; a catch member carried by said body and movable longitudinally thereof; a handle on said body adapted to be grasped between two fingers of a hand; a push button extending through said handle and adapted to be moved transversely of said body when depressed by a thumb; and means operatively connecting said catch member and said push button for translating said transverse movement of said push button into a longitudinal movement effective to move said catch member.

4. In a catch, the combination of: a body; a catch member carried by said body and movable relative thereto; a handle on said body adapted to be grasped between two fingers of a hand; a push button extending through said handle and adapted to be depressed by a thumb; a primary operating member operatively connecting said catch member and said push button; and a secondary operating member carried by said body

and operable to move said catch member through said primary member when said push button is depressed.

5. In a catch, the combination of: a body; a catch member carried by said body and movable longitudinally thereof; a handle on said body adapted to be grasped between two fingers of a hand; a push button extending through said handle and adapted to be moved transversely of said body by a thumb; a primary operating member operatively connecting said catch member and said push button; and a secondary operating member carried by said body and operable to move said catch member longitudinally of said body through said primary member when said push button is depressed.

6. In a catch, the combination of: a body; a catch bar carried by said body and movable relative thereto; a handle on said body, said handle having an opening therein; a primary operating member operatively connected to said catch bar; a push button on said primary member, said push button extending through said opening in said handle and being depressible to move said primary member; and a secondary operating member carried by said body and operable to move said catch member through said primary member when said push button is depressed.

7. In a catch, the combination of: a body; a catch bar carried by said body and movable longitudinally thereto to an advanced and a retracted position; a handle on said body, said handle having an opening therein; a primary operating member operatively connected to said catch bar; a push button on said primary member, said push button extending through said opening in said handle and being depressible to move said primary member; a secondary operating member carried by said body and operable to move said catch member from said advanced to said retracted position through said primary member when said push button is depressed; and resilient means for moving said catch member from said retracted to said advanced position.

8. In a catch, the combination of: a body; a catch bar carried by said body and movable relative thereto, said catch bar having an opening therein; a handle on said body, said handle having an opening therein; a primary operating member having a portion thereof sliding freely in said opening in said catch bar; a push button on said primary member, said push button extending through said opening in said handle and being depressible to move said primary member; and a secondary member pivoted relative to said body and to said primary member and operable to move said catch member through said primary member when said push button is depressed.

9. In a catch, the combination of: a body; a catch member carried by said body and

movable relative thereto; a handle on said body adapted to be grasped between two fingers of a hand; a push button extending through said handle and adapted to be moved transversely of said body when depressed by a thumb; toggle means operatively connecting said catch member and said push button for moving said catch member relative to said body when said push button is depressed; and means for frictionally engaging said body and retaining said toggle means in operating relationship to said catch member and said push button.

10. In a catch, the combination of: a body; a catch bar carried by said body and movable relative thereto; a handle on said body, said handle having an opening therein; a primary operating member operatively connected to said catch bar; a push button on said primary member, said push button extending through said opening in said handle and being depressible to move said primary member; a retaining member frictionally secured to said body; and a secondary operating member carried by said retaining member and operable to move said catch member through said primary member when said push button is depressed.

11. In a catch, the combination of: a retaining member frictionally secured to said body; a body adapted for detachable connection to a support; a catch member carried by said body and movable in said retaining member; a handle detachably secured to said body adapted to be grasped between two fingers of a hand; a push button extending through said handle and adapted to be moved transversely of said body when depressed by a thumb; and means operatively connecting said catch member and said push button for moving said catch member relative to said body when said push button is depressed.

12. In a catch, the combination of: a body adapted for detachable connection to a support; a catch member carried by said body and movable relative thereto; a handle on said body adapted to be grasped between two fingers of a hand; a push button extending through said handle and adapted to be moved transversely of said body when depressed by a thumb; and toggle links operatively connecting said body, said catch member and said push button for moving said catch member relative to said body when said push button is depressed.

13. A catch as defined by claim 12 in which said push button is formed integrally with one of said toggle links.

In testimony whereof, I have hereunto set my hand at Los Angeles, California, this 13th day of September, 1929.

GEORGE R. ADAMS.

CERTIFICATE OF CORRECTION.

Patent No. 1,795,590.

Granted March 10, 1931, to

GEORGE R. ADAMS.

It is hereby certified that error appears in the printed specification of the above numbered patent requiring correction as follows: Page 4, lines 29 and 30, claim 11, strike out the words "a retaining member frictionally secured to said body;" and insert the same after the word "support" in line 32, same claim; and that the said Letters Patent should be read with this correction therein that the same may conform to the record of the case in the Patent Office.

Signed and sealed this 21st day of April, A. D. 1931.

(Seal)
